UNITED STATES PATENT OFFICE.

H. L. THISTLE, OF NEW YORK, N. Y.

SPRING BED-BOTTOM.

Specification of Letters Patent No. 31,196, dated January 22, 1861.

To all whom it may concern:

Be it known that I, H. L. THISTLE, of the city, county, and State of New York, have invented certain new and useful Improvements in Spring-Bottoms for Bedsteads; and I do hereby declare that the following is a full, clear, and exact description thereof, reference being had to the accompanying drawings, making part of this specification, 10 in which—

Figure 1, is a plan of the spring bottom; Fig. 2, a cross vertical section; and Fig. 3, a longitudinal vertical section.

The same letters indicate like parts in all 15 the figures.

Spring bottoms for bedsteads, as they have heretofore been made with helical or spiral springs, are very expensive on account of the necessity of using a very large 20 number of springs to present a sufficient extent of supporting surface, as it will be obvious that no support is afforded to persons lying on the bed in the spaces between the springs, and the required support has here- 25 tofore been obtained only, by a multiplicity of springs. Another objection is the difficulty of taking out broken springs and replacing them which requires an upholsterer. And as servants cannot take them apart they 30 cannot be readily cleaned and moved. By my improvements I avoid all these objections.

In the accompanying drawings (a) represents a bedstead which may be of any suitable construction, but provided with cross bars (b, b, b) which I prefer to secure by putting the ends thereof into notches in two strips (c, c) secured to the inside of the side rails, so that they can be readily put in and 40 taken out. These bars are provided on their upper surfaces with projecting knobs (d) to fit into the lower ends of a series of helical springs (e) so as to hold the said springs in place, and yet admit of removing and re-

placing them readily. Three such bars and 45 three rows of such springs I have found sufficient, but I do not wish to confine myself to such number. Above the helical springs there is a series of spring slats (f) which I prefer to make of wood, there being one such 50 slat for each helical spring in a row, and the under side of these slats are provided with projecting knobs (g) which fit into the upper ends of the helical springs. The ends of the slats are held in proper position by 55 being inserted in mortises in two rails (h, h) secured to the inside of the head and foot board or rails of the bedstead. The helical springs are first put onto the knobs (d), on the cross bars (b) and then the 60 slats (f) are bent up and the ends inserted in the mortises of the head and foot rails and as they spring down the knobs (g) on their under faces are let into the upper ends 65 of the helical springs, which should be of such height as to make the slats spring up in the middle of their length, that being the part which has to sustain the heaviest weight. By these means a spring bottom is formed having a much larger extent of bearing 70 surface for the number of springs employed, than by any other known mode, the whole can be readily taken apart for the purpose of cleaning or moving, or for taking out and replacing any of the parts which 75 may be broken. And when put together the springs are supported in the required position.

What I claim as my invention, and desire to secure by Letters Patent is—

The arrangement of the helical springs on cross bars, substantially as described, in combination with the longitudinal slats above them, substantially as described.

H. L. THISTLE.
